FLEXIBLE METAL FREEZING TRAY

Harvey D. Geyer, Dayton, Ohio, assignor to General Motors Corporation, Detroit, Mich., a corporation of Delaware

Application March 2, 1936, Serial No. 66,616

7 Claims. (Cl. 62—108.5)

This invention relates to freezing trays such as are ordinarily used in household refrigerators for freezing water or other liquids into solid frozen blocks.

5 An object of this invention is to provide a distortable freezing tray of simple and efficient form and which may be readily distorted to facilitate the removal of its frozen contents.

Another object is to provide such a freezing tray wherein the ice block compartments may be held in slightly contracted form by distortion of the metal thereof until the ice is fully frozen, and having means for releasing the contracting means which will permit said metal compartments to slightly increase in size and thereby facilitate the loosening of the frozen ice blocks therefrom.

Another object is to provide a distortable metal freezing tray having means for either positively contracting or expanding the size of the ice block compartments to facilitate removal of the frozen contents thereof.

Further objects and advantages of the present invention will be apparent from the following description, reference being had to the accompanying drawing wherein a preferred embodiment of the present invention is clearly shown.

In the drawing:

Fig. 1 is a plan view of a two-row ice tray made according to this invention.

Fig. 2 is in part a side elevation and in part a section taken on line 2—2 of Fig. 1.

Fig. 3 is a section on line 3—3 of Fig. 1.

Fig. 4 is a longitudinal section thru one ice cup and illustrates the ejection of the ice block by mechanically contracting the flexible metal walls thereof upon the ice.

Fig. 5 is a transverse section similar to Fig. 3 and illustrates the two separate ice blocks freed from the two flexible metal cups by distortion of the flexible walls of said cups.

Similar reference characters refer to similar parts throughout.

The flexible metal tray 10 shown in the drawing comprises ten seamless drawn metal cups 11 which are welded or otherwise fixed together along their upper contacting edges 12 and 13 to form a unitary container. Each metal cup 11 is provided with an interiorly projecting fold or ridge 15 in the metal thereof in order to provide individual expandability or contractability for each cup. In other words, the folds 15 in each cup 11 form transverse lines of relatively easy flexure therein so that each cup 11 may be easily slightly elongated by tension thereupon,

or slightly shortened by compressing same upon its two ends which lie parallel to the fold 15 therein. Obviously when the cups 11 are arranged to form a tray as shown in Fig. 1, all of said cups may be slightly elongated by tension applied only at the two ends of the tray 10; and conversely the cups 11 may be slightly shortened by compression or the forcing of the two ends of tray 10 closer together. In both cases the cups 11 are so distorted as to loosen the frozen 10 ice blocks therefrom.

Furthermore such a tray 10 may be readily bent upwardly at its central portion and downwardly at its end portions, which bending movement obviously will flex the metal walls of the 15 individually flexible cups 11 in such a manner as to entirely or partially free the frozen bond between the ice blocks and cups 11, whereby to facilitate their removal from the tray.

Furthermore such a tray 10 may be readily 20 distorted by a twisting or warping action by twisting one longitudinal end of tray 10 in one direction and the opposite end thereof in an opposite direction. This twisting distortion of the tray as a whole will flex or distort each cup 25 11 a slight amount and thereby facilitate the loosening of the ice blocks from their frozen bond to the metal walls.

If desired, all of the above-mentioned ways of 30 distorting tray 10 may be done by grasping the tray with both hands in order to loosen the ice blocks from their frozen bond to the cups 11.

However in the form shown in the drawing, I have illustrated a hand-cranking mechanism 20 for either elongating or stretching tray 10 beyond 35 its normal length, or shortening or compressing tray 10 less than its normal length. In both cases the flexible metal cups 11 are slightly changed in shape so as to facilitate the loosening of the frozen ice blocks therefrom. 40

Mechanism 20 comprises a longitudinally extending rotatable shaft 21 which is suitably mounted at each end of tray 10 and preferably also at one or several bearings 22 along its length. At the rear end of tray 10 a metal end-plate 23 45 is welded or otherwise strongly fixed to both the end cups 11 and serves as an end reinforcement to the tray. A similar front end-plate 24 is strongly fixed to the two front end cups 11. Shaft 21 has a screw-threaded rear end 25 which 50 is threaded into the bearing 26 in the rear end-plate 23. Shaft 21 has a small collar 27 fixed thereon immediately adjacent its bearing in the front end-plate 24. Plate 24 has fixed thereto by any suitable means an apertured metal mem- 55

ber 28 having an annular flange 29 which engages collar 27 on its front surface. Thus it is seen that shaft 21 may rotate freely in its bearing in the front end-plate 24 but cannot move longitudinally relative thereto. Shaft 21 has a suitable crank handle 30 by which shaft 21 may be rapidly and easily rotated by hand and thereby cause its threaded end 25 to screw into or out of its threaded bearing 26 in the rear end-plate. 5 When shaft 21 is turned in such direction as to screw its end 25 into the rear bearing 26 obviously the two end-plates 23 and 24 are moved closer together, thus shortening the length of the tray 10 by a small compressive distortion on 10 each of the cups 11. When shaft 21 is rotated in the other direction the tray 10 is stretched or made longer by a small expanding distortion of each of cups 11. Obviously then the flexible caps 11 may be either expanded or contracted beyond 15 their normal length or usual shape simply by rotating the crank 30.

In operation, tray 10 is filled to the desired level with water or other liquid to be frozen and placed in a freezing compartment until the liquid 20 is frozen solid and incidentally bonded to the metal surfaces by a frozen bond. The ice blocks may be loosened from tray 10 simply by turning the hand crank 30. If crank 30 is turned in the direction to lengthen the tray 10, as described 25 above, each of the metal cups 11 is slightly stretched out beyond its normal length and thereby the metal walls contacting the ice are so distorted as to peal or break the frozen bond between the ice and walls. Thereafter all the 30 ice blocks may be readily picked out individually by hand, or the entire contents may be dumped out by inverting the tray 10.

If crank 30 is turned in the direction to compress or shorten tray 10, as described above, 35 each of the metal cups 11 has its two tapered end walls 14 compressed upon the ice block therein and its other metal walls slightly distorted to free the frozen bond with the ice. The movement of the tapered end walls from their dotted 40 position 14' (shown in Fig. 4) to their full line position 14 causes the contained ice block to cam upwardly where it can be easily grasped with the fingers or ice tongs. The folds 15 in each metal cup 11 obviously provide for a slight distortion of the side walls and bottom wall of each metal cup 11 when said cups are either stretched 45 or compressed.

If the tray 10 is materially compressed beyond its natural or normal length by the operation of the screw shaft 21 (or by any other suitable 50 means) before the water is frozen therein, the frozen ice blocks of course will be molded in the cups 11 in conformity with their distorted shape. Hence if the distorting force upon cups 11 be removed after the ice blocks are solidly frozen, these metal cups 11 have an inherent tendency 55 or spring action to return to their normal shape and in so doing will automatically distort sufficiently to free the frozen bond with their contained ice blocks. If this automatic freezing action be used it will be unnecessary to stretch tray 10 by manual force upon crank 30 and hence the

collar 27 and its cooperating metal flange 29 may be omitted.

While the embodiment of the present invention as herein disclosed, constitutes a preferred form, it is to be understood that other forms might be adopted, all coming within the scope of the claims which follow.

What is claimed is as follows:

1. A freezing tray comprising: a distortable metal container having a series of distortable ice-block compartments, and a longitudinal rod extending along the central portion of said tray and manually actuatable to distort said container to facilitate the loosening of the ice block therefrom. 15

2. A freezing tray comprising: a distortable metal container having a series of distortable ice-block compartments, and a rotatable shaft extending along the central portion of the tray and attached thereto and manually rotatable to distort said container to facilitate the loosening of the ice blocks therefrom. 20

3. A freezing tray comprising: a distortable metal container having a series of distortable ice-block compartments, and a rotatable shaft attached to said tray exterior to its ice compartments and manually rotatable to distort said container to facilitate removal of the ice blocks therefrom. 25

4. A freezing tray comprising a series of flexible metal ice block compartments which are distortable to both increased and decreased size, and force-multiplying mechanism attached to said tray and manually selectively operable to either increase or decrease the size of said compartment 30 to facilitate the loosening of the frozen ice blocks therefrom.

5. A freezing tray comprising: a flexible metal container having a series of ice-block compartments, and force-multiplying mechanism attached to said tray and reacting with a relatively large force upon opposed end portions of said container and manually operable by a relatively small manually exerted force to distort said ice block compartments after the ice blocks are 45 frozen therein and bonded thereto and thereby loosen the frozen ice blocks therefrom. 40

6. An elongated freezing tray comprising: a series of distortable metal ice pockets, and an actuating rod mounted upon said tray and extending longitudinally with the longer dimension of said tray and reacting upon opposed end portions thereof, said rod being manually actuatable to stretch said metal ice pockets and thereby facilitate the removal of the frozen ice blocks 55 therefrom. 50

7. A freezing device comprising a series of flexible metal ice-block compartments fixed together end to end in a row, and force-multiplying mechanism reacting with a relatively large force upon opposite ends of said row of compartments and manually operable by a relatively small applied force to stretch said compartments by distortion thereof and thereby facilitate the removal 60 of the frozen ice blocks therefrom. 65
